SHEET ENERGY RADIATOR

Chester H. Braselton, New York, N. Y., assignor
to Sirian Lamp Company, Newark, N. J., a cor-
poration of Delaware

Application August 19, 1930, Serial No. 476,341

4 Claims. (Cl. 176—1)

This invention relates to devices and apparatus for producing a flat sheet of energized radiating area adapted for use either as a source of illumination or as a source of radiated energy for various other uses, including that of therapeutics, stimulation of plant growth, photography, signal transmission, and other uses.

One of the objects of my invention is to provide a radiating energy source which has an enlarged area of distribution in contradistinction to radiating energy source confined to a point or along a line.

Another object of the invention is to provide a radiating energy source which may be utilized for illumination or other purposes, and which is adapted to conform to definite limited boundaries so that in the case of illumination, for example, the apparatus may be used for advertising, communication or similar purposes.

An additional object is to provide an illuminating device which may be so constructed as to provide a replaceable sign unit, such, for example, as the various letters of the alphabet.

Another object of the invention is involved in the provision of radiating devices which may be utilized for color or other artistic or advertising effects.

Various other objects will become evident on consideration of the description of a specific embodiment of the invention hereinafter set forth, and in connection with the accompanying drawing, in which

Fig. 1 is a view of a unit or lamp embodying one form of a sheet radiating device, which may be preferred;

Fig. 2 is a view of a modification of the radiating device or lamp;

Fig. 3 is a plan section thereof; and

Fig. 4 is a further modification showing a different configuration of the radiating structure.

The present invention is intended to be used in connection with the energy radiator of the type described in my co-pending application, Serial No. 459,048 filed June 3, 1930. In this application I have described in detail a type of radiator wherein an electric discharge is made to form about a metallic conductor in a gaseous medium of such pressure as to confine the gas discharge path within prescribed limited areas adjacent to the metallic conductor.

In accordance with the invention of the application hereinabove mentioned, I utilize an envelope 10 of transparent or translucent material in which is contained an inert gas, such as a mixture of neon and argon, at a pressure of about

200 mm. of mercury. Mounted on the stem 11, within the envelope, are supports 12 and 13 which are adapted to engage the elliptical conductor 14, which may be of refractory material such as tungsten. The supports also are preferably made of refractory material, such as tungsten, although nickel may be employed provided tungsten is utilized adjacent the emitter where the temperature is highest, and are spot-welded or otherwise attached to the emitting element 14. 10

The emitter 14 is coated throughout its length with a material which, when heated, emits electrons in greater density than ordinary metals or substances such as tungsten or copper. This coating, in its final form, may be of various component parts, but I have found satisfactory a mixture produced by combining barium carbonate, calcium carbonate, and barium nitrate with a binder of sufficient nitrocellulose, dissolved in amyl acetate, to hold the coating on the wire. 20 The proportions of these substances were chosen as 40 grams of barium carbonate, 40 grams of calcium carbonate, and 8 grams of barium nitrate. This coating 15, of calcium and barium carbonates, is secured to the tungsten base 16 25 of the emitter 14 and activated preferably by the means described in my co-pending application hereinabove referred to.

In accordance with this activation method, the mixture in the proportions above mentioned, is 30 applied to a base in the shape of the filament, as indicated at 16 in Fig. 1. The filament is then appropriately mounted on the base supports 12 and 13 on the stem 11, and the stem sealed in the bulb or envelope 10. The exhaust pump is then 35 connected to the bulb and an oven lowered thereupon to raise the temperature of the bulb and contents to about 400° C., or to as high a temperature as the envelope will stand without softening. Simultaneously electric current is passed 40 through the filament which is thus heated to red heat of approximately 600° C. The heat and exhausting process is continued until there is no fluorescence when the high tension current is directed against the wall of the bulb, or in other 45 words, until there is practically no more gas inside of the bulb. A vacuum of about one-half of a micron is an approximate limiting value.

The current is then increased through the filament so that the temperature thereof is slowly 50 raised until it is about 800 degrees, or a bright red color, the exhaust operation being continued until the newly emitted gases are removed. The oven is then raised from the bulb and the filament heated to about 1200° C., the pumping being 55

continued until a high vacuum of one-half micron is again obtained.

The pump is then shut off, the current turned off, and about one-half mm. of neon gas emitted 5 to the bulb. The filament current is then turned on and gradually increased until a diffused glow completely fills the bulb. When the discharge is uniform throughout the bulb, which usually occurs in less than ten minutes, the so-called activating process for the filament coating is completed. Should white discharge spots appear on 10 the filament or support rods, it is an indication that the gases or vapors within the bulb have not been completely removed, and the bulb is again exhausted and the whole process of activation 15 repeated. When the activating process is finally complete, the filament temperature is raised for a moment to about 1400° C., and the pumping operation is again resumed to remove any undesirable 20 gases which may have been thrown off during the activation process.

The filament circuit is then disconnected and the pump turned off and the appropriate amount of gas admitted to the bulb. In one form of my 25 invention I utilize neon and argon gases in the relative amounts of 50 mm. of neon gas, and 150 mm. of argon. The bulb is then sealed off and a small quantity of magnesium flashed to absorb additional impurities, thus completing the 30 process.

The device, as completed in accordance with the above process, may be energized by electric current, either alternating or direct, to cause formation of a halo or layer of highly active 35 gases adjacent the coated conductor. The depth of this layer is dependent upon certain variables, such as the pressure of the gas and voltage applied to the bulb terminal, and where a single straight radiator is employed, the halo would be 40 of approximately uniform cross-section and adjacent the length of coated material. In the form of my invention illustrated in Fig. 1, however, I have divided the filamentary coated conductor in the shape of an ellipse, the ends of which are attached to the supports 12 and 13. Consequently, 45 the halo 17, which has a highly energized gas area, tends to contract and diminish the unenergized space bounded by the ellipse, this contracting operation commencing at both ends and 50 progressively moving toward the center of the ellipse until the inner elliptical area is completely energized, provided the dimensions of the ellipse are not too large in proportion to the thickness of the halo or layer on the conductor.

55 It is readily apparent that where a complete closed sheet is undesirable that the branches of the conductor may be sufficiently separated to maintain the partial unity of each conducting branch with possibly a sheet effect diverging the 60 ends of the branches and open areas between each branch. It is also apparent that any number of electrically parallel circuits may be employed, depending upon the results desired.

Other monatomic gases such as krypton, 65 helium, or metal vapors such as those of mercury, caesium, and rubidium may be used either alone or in combination with each other or with neon and argon.

70 Where the device is to be utilized for illumination, this construction provides a highly energized gaseous area in sheet form, which may be utilized for illumination at right angles to the plane of the sheet. By varying the contained gases a variety of light effects may be obtained 75 which may be used for various light or other

radiation effects. For example, a mixture of argon, caesium, and neon with the argon predominating, produces a white light. Red is produced by neon and rubidium, with neon predominating. Yellow is produced by neon, mercury, and caesium, with neon predominating; blue, by a mixture of argon, mercury, and rubidium, with argon predominating; ultra-violet by a mixture of argon, mercury, and helium, with argon and mercury predominating; and infra-red by a mixture of helium and neon with mercury predominating. In all of these mixtures, at least five percent of helium is desirable, but not essential, as aiding the conductivity of the gas mixture. Where the device is used for energy radiation 15 other than illumination, it is seen that the invention provides means for concentrating a large amount of energy normal to the energized sheet, this obviously having a number of practical applications. 20

As it is the tendency of the energized gas to develop into a sheet between closed boundaries, it is obvious that the operation is independent of the configuration of the bounding limits. These limits may take the shape of letters of the alphabet or any fanciful design or object which would adapt the invention for use in the field of advertising or communication of intelligence, as well as for illumination, or for the application of energy of selected frequency for a variety of 30 specific purposes.

In Fig. 4 of the drawing is illustrated a possible variation in a star shape figure 20 having supporting contacts 21 and 22 by which electric current is introduced and conducted to the figure. 35 On energization of the parallel conductors 23 and 24, the halo forms on the conductors and then spreads over the bounded area to form a star-like sheet of energy radiating gas.

In Fig. 2 of the drawing I have illustrated a 40 modification of the invention. Within the envelope 10, and mounted on the stem 11, is a plurality of upstanding supports 32, 33, 34, and 35. Attached to the upper ends of these supports, as by spot-welding or by wrapping of the adjacent 45 parts together, is a spiral radiator 36, formed of a tungsten base 37, on which the coating of radiating material 38 is similar to that described in connection with the radiator 14 of Fig. 1. Inspection of the drawing shows that the spiral 36 50 expands from its innermost end to its outer end.

Within the envelope 10 is a gas, preferably inert, such as argon and neon, as described in connection with the structure of Fig. 1.

The operation of the radiator, as above described and illustrated in Fig. 2, is as follows: When the potential is applied to the outer terminals of the device, the electric current passing through the filament 37 heats the coating 38 and causes the formation of an adjacent layer of 60 ionized gases, in accordance with the principles described in connection with Fig. 1. At the point *a*, where adjacent portions of the spiral are closest together, the ionized gaseous atmosphere combines to form an active area in between these 65 adjacent sections. This area tends to activate the gas intermediate the spiral segments toward the point *b* along the spiral, and causes progression of ionization to a point in the spiral where the ionized atmosphere is so attenuated that the energized area ceases to progress, thus forming a permanent or limiting point for the active 70 ionized gases intermediate the adjacent portions of the spiral. A steady state having been arrived at, there is thus produced a spiral sheet of 75

activated gas which functions to radiate energy in the form of luminous energy, or in other forms, dependent on the gases and other variables chosen.

- 5 It is pointed out that when intermediate regions between the adjacent turns of the spiral are activated, a dual path is provided for current flow, consisting of the metallic conductor 37 with its coating 38 and the energized atmosphere 10 adjacent this conductor. In order to prevent an actual short-circuiting of the metallic conductor by means of the active gas, it is necessary that the degree of divergence of the spiral and the actual distances between adjacent portions of the 15 spiral be such as to prevent short-circuiting effects.

The breakdown potential of the gases used along the axis of the conductor should be below the potential necessary to raise the coating on 20 the conductor to such a temperature as to cause the coating to emit electrons profusely. Where reference is made in the claims to "electron emitting temperature", it is meant by this expression that the emission is sufficiently dense to permit 25 functioning of the discharge, and since the potential when this condition is arrived at is reached at a point above the potential necessary for a breakdown discharge to occur along the conductor through the gases, the conditions are appropriate for the formation of the activated gas 30 layer hereinabove referred to.

It should be mentioned further that while the coating of the conductor is described and illustrated as a part external to the conductor coil, it may also be applied internally of the coil as by 35 forcing the material while in a plastic state into the coil interior and subsequently hardening, or by forming the material into a rod or pencil which may be positioned interior of the coil.

40 In the claims the expression "an electron emitting coating on said - - - conductor" is intended to cover either of these alternative positionings of the coating.

Various other modifications of the invention 45 providing for a sheet radiator may be employed, such modifications, however, coming within the terms of the claims hereto appended.

Having thus described my invention, what I desire to claim is:

50 1. An electrical discharge device comprising an envelope, a divided conductor constituting the sole source of the discharge of the device within said envelope forming parallel conducting paths, a gas within said envelope surrounding

said divided conductor, and means including a coating of material on said conductor containing alkaline earth metal oxides to render said gas highly conductive in a limited region intermediate the segments of the divided conductor when the conductor is heated and a potential applied to the ends thereof whereby a sheet halo of substantial size is formed between said segments.

2. An electrical discharge device comprising an 10 envelope, a filamentary divided conductor constituting the sole source of the discharge of the device within said envelope forming parallel conducting paths, an electron emitting coating containing alkaline earth metal oxides on said divided conductor, and an inert gas surrounding 15 said conductor, the pressure of said gas being sufficient to confine the densely ionized portion thereof to the vicinity of said conductor when said conductor is raised to electron emitting temperature and to permit the formation of a sheet halo between the sections of the divided conductor.

20 3. An electric lamp comprising an envelope, a filamentary helically wound conductor constituting the sole source of illumination of said lamp and forming a closed circuit conductor within 25 said envelope, connecting conductors connected to separate points of said closed circuit conductor, a coating of electron emitting material containing oxides of the alkaline earth metals on said closed circuit conductor, and an ionizable gas containing argon and neon within said envelope having a pressure such that the major ionization of said gas is confined to the area of gas enclosed by said closed conductor and immediately 30 surrounding the same, and that a sheet form halo of substantial area is formed within the closed circuit of the conductor.

35 4. A radiating device comprising an envelope 40 containing ionizable gases, a divided electric conductor constituting the sole source of radiation of the device within the envelope, electric conductors connected to said divided conductor at separate points thereof, and a coating of electron emitting material containing oxides of the 45 alkaline earth metals on said conductor, said gases including argon and neon and a trace of metal vapor and having a combined pressure preferably in excess of 150 mm. of mercury and sustaining the formation of a substantial sheet form 50 halo between the divided sections of the conductor when a current is passed through the conductor.

CHESTER H. BRASELTON.
